his Attorney

UNITED STATES PATENT OFFICE.

CHARLES M. WILLS, OF ATLANTIC CITY, NEW JERSEY

WEARING APPAREL.

Application filed November 19, 1921. Serial No. 516,261.

To all whom it may concern:

Be it known that I, CHARLES M. WILLS, a citizen of the United States, residing at Atlantic City, in the county of Atlantic and State of New Jersey, have invented a new and useful Improvement in Wearing Apparel, of which the following is a full, clear, and exact specification.

The device of my invention refers to children's wearing apparel and refers particularly to diapers.

There are many objectionable features incident to the generally employed diapers, among which may be mentioned the necessity of pins with their accompanying inconvenience to the person applying the article and the danger to the wearer; the use of buttons or metallic fasteners, which are liable to cause discomfort and which do not allow of a change of size of the article; the liability to attach the article in too loose or too tight condition, resulting in ineffectiveness, or discomfort, and the difficulty of proper arrangement due to the movement of the wearer.

The device of my invention overcomes all of these objectionable features and presents a diaper which can be employed without the use of separate pins and hard fastening means, and hence, is free from the inconvenience and danger of their use; which can always be applied in a uniform condition of looseness, thus being always effective and comfortable, and which can be readily and rapidly arranged without disengagement during its application.

The device of my invention comprises a body portion of suitable material carrying a plurality of bands and means whereby the bands may be employed to affix the device in any desired degree of tightness, or looseness, upon the body of an infant.

In the accompanying drawings, illustrating one form of the device of my invention, similar parts are designated by similar numerals.

Figure 1 is a plan view showing my device in folded form.

Figure 2 is a development of the device of Figure 1.

The particular form of the device of my invention, shown in the accompanying draw-

ings, comprises a triangular body portion 10, to which is attached a waist band 11, carrying the loops 12, 13, 14 and 15. Fixedly attached to the body portion 10 are the side bands 16 and 17 and the central band 18.

To employ the device, the infant is laid upon the device with the waist band 11 positioned at its waist line. The waist band 11^a is then brought forwardly around the waist of the infant, passed through the loop 15 and tied thereto. The waist band portion 11^b is brought forwardly around the waist of the infant, passed through the loop 13 and tied thereto. The central band 18 is then brought up forwardly between the legs of the infant, passed through the loop 12 and tied thereto, and finally the side bands 16 and 17 are passed through the loops 13 and 15, respectively, and tied thereto.

The device, as shown in Figure 2, has thereupon been folded along the indicated dotted lines and assumes the position shown in Figure 1.

It is evident that the waist band 11 can be so positioned as to allow of its necessary and comfortable placement around the waist of the infant and that, by means of the bands 16, 17 and 18, the device can be so positioned as to allow of the free movement of the infant's legs, without interfering with the purposes of the device.

My invention, therefore, presents a device of the described character, free from pins and undesirable hard fastening means and of such construction that it can be readily and properly fitted to an infant without discomfort and danger.

I do not limit myself to the particular size, shape and number of parts, as shown in the example, which is described simply as a means for clearly explaining my invention.

What I claim is:—

In a device of the character specified, in combination, a triangular body portion, a waist band carried by the body portion, a loop carried by the waist band at approximately one angle of the body portion, two loops carried by the waist band each approximately one-quarter inwardly distanced from an angle of the body portion, a band carried by the end portion of the body por-

tion opposite the waist band capable of being inserted through the first mentioned loop when the device is folded and a band carried by each side of the body portion not attached to the waist band capable of being inserted through one of the second mentioned loops when the device is in folded position.

Signed at Atlantic City, in the county of Atlantic and State of New Jersey, this 16 day of November, 1921.

CHARLES M. WILLS.
Witness:
F. C. ROBBINS.
